UNITED STATES PATENT OFFICE.

WILLIAM J. SMITH, OF NEW YORK, N. Y.

ATTACHMENT FOR GUITARS.

1,223,744.

Specification of Letters Patent. Patented Apr. 24, 1917.

Application filed January 8, 1916. Serial No. 70,960.

To all whom it may concern:

Be it known that I, WILLIAM J. SMITH, a citizen of the United States, residing at New York, in the county and State of New York, have invented certain new and useful Improvements in Attachments for Guitars, of which the following is a full, clear, and exact specification.

This invention relates to guitars, and has for its object to provide improved means for readjusting the strings in order to change the tone and thus cause an ordinary guitar to sound substantially like a Hawaiian guitar.

15 The invention contemplates the use of a metallic supporting member for the strings, such metallic member being detachably placed over the nut arranged at the outer end of the handle. A special object of the 20 present invention is to so construct the re-adjuster or detachable support that it will not be apt to become accidentally displaced while the instrument is in use.

25 The invention will be first hereinafter described in connection with the accompanying drawings, which constitute part of this specification, and then more specifically defined in the claims at the end of the description.

30 In the accompanying drawings, wherein similar reference characters are used to designate corresponding parts throughout the several views:

35 Figure 1 is a plan view of an ordinary guitar before my improved re-adjuster is attached.

Fig. 2 is a plan view of the outer end portion of the neck of the instrument showing the re-adjuster in operative position.

40 Fig. 3 is a side view of the outer end portion of the neck, showing how the inverted U-shaped re-adjuster straddles the nut and rests upon the neck at opposite sides thereof, and

45 Fig. 4 is a perspective view of the re-adjuster.

Referring more particularly to the drawings, 1 designates the body of an ordinary guitar having the usual neck 2 carrying the frets 3, the nut 5 and keys 7. The strings 6 pass from the keys 7 through notches in the nut 5 and along the neck to the opposite

end of the body 1 where they are secured at 8. Any desired form of bridge 4 may be employed, its construction not affecting the invention.

55 The re-adjuster 9 is made of metal and is substantially U-shaped. When it is attached to the instrument, it is inverted and slipped over the nut 5, as illustrated in Figs. 2 and 3, so as to rest on the neck 2 at opposite sides of the nut. Grooves 10 are formed in the outer face of the re-adjuster corresponding to the grooves in the nut. When attached as described, the re-adjuster serves to raise the strings 6 and provides 60 them with a hollow metallic support which gives the desired variation in tone. Because of the inverted U-shape of the re-adjuster, the same straddling the nut, the ordinary use of the instrument will not displace the 65 readjuster, as might be the case if said re-adjuster did not completely straddle the nut and rest upon the neck at both sides thereof.

Having thus described my invention, what I claim as new and desire to secure by Letters Patent of the United States is:

75 1. A removable attachment for changing the tone of an ordinary guitar to simulate that of a Hawaiian guitar, comprising a metallic support to rest upon the neck of the 80 instrument for holding the strings off of the nut.

2. A removable attachment for changing the tone of an ordinary guitar to simulate that of a Hawaiian guitar, comprising an 85 inverted U-shaped metallic support to straddle the nut and rest upon the neck of the instrument for holding the strings off of the nut.

90 3. A clip for stringed instrument nuts adapted to fit detachably over the ordinary nut of a stringed instrument, and having side members adapted to contact with and rest upon the portions of the instrument on opposite sides of said ordinary nut, said side 95 members being higher than the sides of said nut whereby the instrument strings will be elevated.

In testimony whereof I have signed my name to this specification.

WILLIAM J. SMITH.
